ATTORNEY

UNITED STATES PATENT OFFICE.

CHARLES FRANCIS PEASE, OF CHICAGO, ILLINOIS, ASSIGNOR TO THE C. F. PEASE COMPANY, OF CHICAGO, ILLINOIS, A CORPORATION OF ILLINOIS.

RULING-PEN.

1,333,129.

Specification of Letters Patent.

Patented Mar. 9, 1920.

Application filed May 10, 1919. Serial No. 296,090.

To all whom it may concern:

Be it known that I, CHARLES F. PEASE, a citizen of the United States, residing at Chicago, in the county of Cook and State 5 of Illinois, have invented certain new and useful Improvements in Ruling-Pens, of which the following is a specification.

My invention relates to improvements in ruling pens.

10 An important object of the invention is to provide a ruling pen having means whereby one of its blades may be shifted to an open position with respect to the other blade, for cleaning the same, together with means 15 to automatically hold the blade in the opened or closed position.

An important object of the invention is to provide a device of the above mentioned character, which is characterized by extreme 20 simplicity, cheapness of manufacture, and convenience in use.

Other objects and advantages of the invention will be apparent during the course of the following description.

25 In the accompanying drawings forming a part of this specification and in which like numerals are employed to designate like parts throughout the same,

Figure 1 is a side elevation of a ruling 30 pen embodying my invention,

Fig. 2 is a central longitudinal sectional view through the same, the swinging blade being shown in the closed position, and,

Fig. 3 is a similar view with the swinging 35 blade in the open position.

In the drawings, wherein for the purpose of illustration is shown the preferred embodiment of my invention, the numeral 5 designates a handle, having a screw-threaded opening 6, for receiving a shank 7, of a coupling 8. This coupling is provided at its opposite end with a screw-threaded opening 9, receiving a shank 10, carried by a base 11. This base is secured to a relatively 45 stationary blade 12.

The numeral 13 designates a swinging or movable coacting blade, provided with a base 14, arranged within a recess 15, in the base 11 and pivoted therein by means of a 50 pin or pivot element 16. This base is provided with cam faces 17 and 18, adapted to

be alternately engaged by a leaf spring 19, disposed within the recess 15, and contacting with the shoulder 20, there being sufficient space behind the leaf spring to permit of its yielding action.

The blade 13 is provided with a transverse screw-threaded opening 20, receiving a screw 21, carrying a milled head 22. This screw also has screw-threaded engagement 60 within an opening formed in a spring 23, secured to the blade 13, as shown at 24. The screw 22 has its free end engaged within a recess 25, formed in the blade 12.

As shown in Fig. 2, the leaf spring 19 is 65 engaging the cam face 17, thereby swinging the blade 13 upon its pivot 16, toward the blade 12, the extent of opening between the ends of these blades being regulated by adjusting the screw 21. In Fig. 3, the blade 70 13 is shown swung to the open position, and its face 18 is engaged by the spring 19, serving to hold the blade in the open position.

It is to be understood that the form of my invention herewith shown and described 75 is to be taken as a preferred example of the same, and that various changes in the shape, size, and arrangement of parts may be resorted to without departing from the spirit of the invention or the scope of the subjoined claim.

Having thus described my invention, I claim:

A ruling pen of the character described, comprising a handle, a blade connected therewith and provided with a base having a longitudinal recess having shoulders formed therein, a coacting blade having a base pivoted within the recess, said base having angularly arranged faces, and a leaf 85 spring seated upon said shoulders extending longitudinally within the recess and adapted to contact with the faces, said leaf spring being held in position upon said shoulders by said base.

90 In testimony whereof I affix my signature in presence of two witnesses.

CHARLES FRANCIS PEASE.

Witnesses:

OSCAR O. MERTZ,
THOMAS LORD.
